DESIGN FOR A LAPEL PIN

Evelyn S. Gravitt, Memphis, Tenn.

Application April 28, 1944, Serial No. 113,406

Term of patent 3½ years

(Cl. D45—19)

To all whom it may concern:

Be it known that I, Evelyn S. Gravitt, a citizen of the United States of America, residing at Memphis, in the county of Shelby and State of Tennessee, have invented a new, original, and ornamental Design for Lapel Pins, of which the following is a specification, reference being had to the accompanying drawing, forming part thereof.

Fig. 1 is a front view of a lapel pin showing my new design.

Fig. 2 is an edge view.

I claim:

The ornamental design for a lapel pin, substantially as shown.

EVELYN S. GRAVITT.
